US00D414159S

United States Patent [19]

Deslyper et al.

[11] Patent Number: Des. 414,159

[45] Date of Patent: ** Sep. 21, 1999

[54] BATTERY PACK

[75] Inventors: **Amy T. Deslyper**, Dacula; **James D. Domoleczny**, Duluth, both of Ga.; **Brian J. Hassemer**, Gurnee; **Mark D. Janninck**, Elmhurst, both of Ill.

[73] Assignee: **Motorola, Inc.**, Schaumburg, Ill.

[**] Term: 14 Years

[21] Appl. No.: 29/088,085

[22] Filed: May 14, 1998

[51] LOC (6) Cl. 13-02

[52] U.S. Cl. D13/103

[58] Field of Search D13/103; 429/96-100,
429/163, 176
